DESIGN FOR A SHOWER HEAD OR SIMILAR ARTICLE

Albert G. Tompkins, Maplewood, N. J.

Application September 12, 1942, Serial No. 108,215

Term of patent 3½ years

To all whom it may concern:

Be it known that Albert G. Tompkins, a citizen of the United States and resident of Maplewood, in the county of Essex and State of New Jersey, have invented a new, original, and ornamental Design for a Shower Head or Similar Article, of which the following is a specification, reference being had to the accompanying drawing forming part thereof, in which:

Fig. 1 is a bottom perspective view of a shower head showing my new design;

Fig. 2 is a top perspective view thereof with the coupling removed; and

Fig. 3 is a top view thereof with the coupling removed.

The dominant features of the design are shown in full lines in the drawing.

I claim:

The ornamental design for a shower head or similar article, substantially as shown and described.

ALBERT G. TOMPKINS,
